HARRY PEASE, OF BARNSDALL, OKLAHOMA, ASSIGNOR TO THE GRAY PROCESSES CORPORATION, OF NEWARK, NEW JERSEY, A CORPORATION OF DELAWARE

REFINING HYDROCARBON DISTILLATES

Application filed July 7, 1927. Serial No. 203,869.

This invention relates to the treatment of fluids with solid adsorbents, and more particularly to refining hydrocarbon products by contacting the same in vapor phase with solid adsorptive material, such, for example, as fuller's earth or the like.

One method of refining hydrocarbon products is to bring such products in vapor phase into contact with a solid adsorptive 10 treating material to polymerize the unstable unsaturated compounds contained in the products. The polymers thus formed being of higher boiling point than the products, are 15 condensed in the treating material and are removed therefrom in liquid form, after which they are preferably refluxed to the still. The treated vapor freed from the unstable unsaturated compounds is collected and stored.

20 After a period of use, the efficiency of the treating material decreases, probably due to the collection therein of substances which adhere to it and clog its active surfaces. Such decrease in efficiency is manifested by a 25 decrease in the quality of the treated vapor. This usually occurs progressively during the treating process until ultimately the quality of the treated product becomes poorer than is desirable. Heretofore it has been the practice at this point either to discontinue operation or by appropriate valves to cause the vapors to contact with a different batch of 30 treating material, the used treating material being revivified for further use. Such procedure is not always convenient, especially when the treating process is being carried on under pressure in connection with a cracking unit for the purpose of treating cracked products.

40 An object of this invention is to increase the efficient life of solid adsorptive material used in the refining of hydrocarbon products, thereby greatly increasing the efficiency of the refining process and decreasing the cost 45 of the treating material.

According to this invention, when the treating material is apparently spent, as evidenced by appropriate tests of the treated vapor, the treating material is reactivated 50 by reducing temporarily the pressure on the

fluids emerging from the treating material. The reactivation of the treating material is apparently caused by the solvent effect of the more rapidly released vapors and liquids, although the exact reason for the reactivation 55 is not known. This method of reactivation may apparently be carried on practically indefinitely and by use of the method it has been possible to prolong the active life of fuller's earth in a treating tower connected with a 60 cross cracking unit until approximately seven thousand barrels of gasoline have been refined by each ton of earth, whereas previously, using the same stock and apparatus, only twelve hundred barrels could be refined before discarding the fuller's earth.

Other objects, novel features and advantages of the invention will be apparent from the following description and accompanying drawings, wherein

70 Figure 1 is a diagrammatic illustration of an apparatus for producing cracked gasoline in which the invention is embodied; and

Fig. 2 is an enlarged view of a modified form of one of the units of the apparatus.

75 10 designates the furnace or tube still of a cracking unit to which the charging stock is supplied through a pipe 11. The still 10 is connected by means of a pipe 12 with the reaction chamber 13, which in turn is connected 80 through the pipe 14 controlled by valve 15 with the vaporizer 16. A pipe 17 leads from the top of the vaporizer 16 to the dephlegmator 18 which preferably is a bubble tower.

85 From the top of the bubble tower 18, a pipe 19 controlled by valve 20 communicates with the top of a treating tower 21. Within the treating tower is provided a funnel-shaped shelf 22 which supports a body of solid adsorptive material, such, for example, as 90 fuller's earth or the like. The shelf 22 is fluid-permeable and terminates in a spout 24 projecting beyond the bottom of the tower 21. A pipe 25 controlled by valve 26 leads from the treating tower 21 at a point below 95 the shelf 22 to a condenser 27 which communicates through a pipe 28 with a gas separator 29 which is provided with a valve-controlled vent 30. A pipe 31 leads from the gas separator 29 to a storage tank, not shown.

A pipe 32 leads from the bottom of the treating tower 21 to the lower portion of a tank or accumulator 33. A pipe 34 controlled by valve 35 leads from the lower portion of the accumulator 33 to a pump 36. The pump 36 communicates through a pipe 37 controlled by a valve 38 with the bubble tower 18 and through the pipe 39 controlled by a valve 40 with the vaporizer 16. The 5 accumulator 33 also communicates through the pipe 41 controlled by valve 42 with a cooler 43, which in turn communicates with a tank 44. The accumulator 33 is provided with a liquid regulator 45 which controls the 10 operation of the pump 36. In Fig. 2, the accumulator 33' is differently connected than the accumulator 33 of Fig. 1. The pipes 32' and 34' are at the same level as in Fig. 1. The pipe 41' leading to the cooler is, however, arranged near the upper part of the 15 accumulator.

In the operation of this apparatus, charging stock is supplied to the still 10 from which it flows to the reaction chamber 13 and thence to the vaporizer 16 by way of the pipe 14 and valve 15. Vaporized hydrocarbons pass through the pipe 17 to the bubble tower 18 where the higher boiling constituents are 20 condensed. The desired fraction, which may be gasoline having a definite boiling range, is led in vapor form through the pipe 19 to the treating tower 21 where it is caused to pass through the solid adsorptive treating material 23. In its passage through the 25 treating material, the unstable unsaturated hydrocarbons present therein are polymerized to higher boiling compounds which condense in the treating material. The treated vapor passes through the pipe 25 to the condenser 27, from thence to the gas separator 29, and is then led by the pipe 31 to suitable storage tanks. The polymers collected in the treating material as well as any other condensate found therein drip through the 30 treating material and collect in the bottom of the treating tower 21 from which they are conducted by means of the pipe 32 to the accumulator 33. From the accumulator 33, the polymers and any other liquid that may 35 have been collected with them are refluxed back into the system by means of the pump 36. The operation of the pump 36 is controlled by the regulator 45 so that sufficient liquid is kept in the accumulator 33 to act as 40 a seal to prevent treated vapor escaping by way of the pipe 32. The cracking unit herein disclosed delivers the vaporized hydrocarbons to the bubble tower at a pressure in excess of atmospheric which pressure is normally 45 maintained in the treating tower and condenser as well as in the accumulator by proper regulation of the valves 28 and 35, valve 42 being closed.

After a period of operation, the treating 50 material begins to lose its efficiency. Even-

tually, its efficiency will become so low that the treated vapor is not satisfactory. The exact limit varies with different installations, and the critical point where the product falls below specification is determined by the use of various well-known tests. When this condition has developed, formerly it has been the practice to discontinue the flow of vapor through the treating tower either by shutting down the cracking unit or more usually by 55 passing the vapors through another tower. The spent treating material is then removed for revivification and fresh material substituted. This is avoided in accordance with the present invention by opening the valve 42, thus putting the accumulator in communication through the cooler 43 with the tank 44 which is preferably maintained at atmospheric pressure. In an apparatus of the type herein disclosed, the vapor in the 60 treating tower is usually maintained under a pressure of approximately thirty pounds, which pressure is maintained in the condenser and in the accumulator. When the valve 42 is opened, the pressure differential thus established causes an increased vapor flow through the treating material, the vapor being carried off from the treating tower through the accumulator to the tank 44 together with polymers and other liquid. As 65 the valve 42 is preferably small and there is a lag due to the height of treating material in the tower 21, the pressure drop caused by opening the valve 42 does not substantially affect pressure of the vapors in the treating tower above the treating material during the comparatively short period during which the valve 42 is open. Such flow for a period of from fifteen to twenty minutes revivifies, in a manner not at present 70 fully understood, the treating material so that the treated vapor is of satisfactory quality. The valve 42 is now closed and normal operation reestablished. Whenever the quality of the treated vapor again falls below 75 standard, the above procedure is repeated. The intervals at which it is necessary to open the valve 42 become shorter and shorter as the run progresses, and it eventually becomes economical to remove the treating material from the treating tower for further reactivation as by reburning. By means of the invention herein described, it has been possible to increase the active life of treating material from approximately twelve hundred barrels per ton to approximately seven thousand barrels per ton in treating cracked gasoline.

The operation of the apparatus when provided with the modified accumulator is quite similar. However, instead of both vapor and fluid flowing to the tank 44, vapor alone flows to this tank. This is because of the fact that the pipe 41' leads from the accumulator at a point above the level maintained in the liquid in the accumulator. With either mod-

ification, however, there is an increased flow of vapor through the treating material which reactivates the treating material.

The utility of the invention is apparent from the fact that, by more than quintupling the active life of the treating material it practically divides the operating expense of the process by five. Moreover, by increasing the life of the treating material to such great extent, it makes unnecessary the standby treating tower ordinarily used in connection with a pair of active treating towers, and thus reduces the actual cost of the installation.

Although the invention has been disclosed and described in connection with an apparatus embodying a cracking unit of the type ordinarily known as the Cross cracking unit, it is not limited to use with such unit but can be used equally effectively in any case where cracked or other vapors are refined by contacting them with a treating material which becomes inactive due to the accumulation of impurities on its surface. The beneficial effect attained by the invention is due to the reduction of pressure on the effluent fluids while the pressure of the crude vapors supplied to the treating tower is maintained. In the case of atmospheric pressure treating, this can be accomplished by connecting the accumulator or tank 44 with a vacuum pump or other source of subatmospheric pressure. Where the accumulator tank is not provided with a liquid level control device, it may be advisable to shut off the pump 36 when the valve 42 is opened.

It is apparent, of course, that various modifications may be made in the structural details of the apparatus above disclosed without in any way departing from the spirit of the invention as defined in the appended claims.

1. In the process of treating vaporized hydrocarbons by passing the same through solid adsorptive material, the step which comprises periodically increasing the pressure differential through the adsorptive material by reducing the pressure applied to the effluent hydrocarbons materially below that applied to the entering hydrocarbons.

2. In the process of treating vaporized hydrocarbons by passing the same through solid adsorptive material at super-atmospheric pressure, the step which comprises periodically increasing the pressure differential through the adsorptive material by reducing materially the pressure on the effluent hydrocarbons while maintaining substantially undiminished the pressure of the entering hydrocarbons.

3. The process of treating vaporized hydrocarbons which comprises passing said hydrocarbons through solid adsorptive material, maintaining super-atmospheric pressure on the entering hydrocarbons and periodically increasing the pressure differential

through the adsorptive material by reducing the pressure applied to the effluent hydrocarbons by causing a portion thereof to flow to a zone of atmospheric pressure.

4. The method of prolonging the useful life of adsorptive treating material interposed in a hydrocarbon vapor stream in such manner that under normal operating conditions both effluent and entering vapors are subjected to substantially the same pressure which comprises periodically increasing the pressure differential through the adsorptive material by materially reducing the pressure to which the effluent treated vapors are subjected.

5. The method of prolonging the useful life of adsorptive treating material interposed in a hydrocarbon vapor stream in such manner that under normal operating conditions both effluent and entering vapors are subjected to at least atmospheric pressure which comprises periodically increasing the pressure differential through the adsorptive material by causing flow of a portion of the effluent vapors to a zone of lower pressure than that to which they are normally subjected.

6. The method of prolonging the useful life of adsorptive treating material interposed in a hydrocarbon vapor stream in such manner that under normal operating conditions both effluent and entering vapors are subjected to super-atmospheric pressure which comprises periodically increasing the pressure differential through the adsorptive material by reducing to atmospheric the pressure applied to the effluent vapors while maintaining substantially undiminished the pressure applied to the entering vapors.

7. The process of passing hydrocarbon vapors under pressure through a bed of adsorbent material, removing liquid products from said material, continuously separating effluent vapors from said liquids while maintaining super-atmospheric pressure thereon and periodically increasing the pressure differential through the adsorptive material by reducing the pressure on the effluent vapors for the purpose of reactivating said treating material.

8. The process of passing hydrocarbon vapors through a bed of solid adsorptive material in such manner that under normal operating conditions both entering and effluent vapors are subjected to substantially the same pressure, removing liquid products from said material, continuously separating effluent vapors from said liquid products while maintaining the pressure on the effluent vapors and periodically increasing the pressure differential through the adsorptive material by reducing the pressure on the effluent vapors.

9. The process of passing hydrocarbon vapors under pressure through a bed of solid

adsorptive material, normally maintaining super-atmospheric pressure on both the entering and effluent vapors, removing liquid products from said material, continuously separating the effluent vapors from said liquid products while maintaining super-atmospheric pressure thereon and periodically reducing the pressure on the effluent vapors to atmospheric.

In testimony whereof, I have signed my name to this specification.

HARRY PEASE.
